ABSTRACT OF THE DISCLOSURE

A line gripping device having an underlying set of pre-formed helical wires applied over the line, and a gripping member having helically formed wires grippingly engaging this underlying set of wires. The gripping member is provided with means for engaging an anchoring device.

This is a continuation of application Ser. No. 748,502, filed July 29, 1968, and now abandoned.

This invention relates to new, different and unobvious line engaging devices, and methods of using such devices for dead ending and pulling lines.

Dead ends are used for gripping wires, cables, strands or other types of lines and find particular application in guying transmission towers, antenna towers, and other structures. The dead ends transfer the pull of the lines to the anchoring structures at both ends of the line, and are also often used to interconnect segment of a line.

There have been several prior art proposals for dead ends suitable for such gripping of lines. One common form of these dead ends is that which utilizes helically formed resilient wires or wire elements for gripping a line, which wires are bent to form a bight for engaging the anchoring structure. One example of this type of dead end is disclosed in U.S. Pat. No. 3,295,311 in the name of T. E. Butz et al. This device has been extremely effective in dead end applications, especially in conjunction with stranded metal wire lines such as guy strand, single elements lines and relatively stiff fiber glass rods. However, with certain types of lines such as fiber glass rope, which are sensitive to crushing and longitudinal displacement of the strands, these devices, while being superior to other gripping devices, still had some tendency to cause crushing and longitudinal displacement of the elements especially under field applied conditions where extreme care was not exercised in applying the grip.

The sensitivity to crushing force is a characteristic of fiber glass rope, and also certain other types of rope formed of strands, each of which strands are made up relatively thin elements. This sensitivity is characterized by a propensity toward weakened areas on the rope caused by concentrated compression forces acting on the rope over a constricted area, damaging the elements. This weakened area is then likely to fail before the rated breaking strength of the line is reached.

Although the dead ends described in said Pat. No. 3,295,311 applied directly to the line reduced the amount of this crushing force as compared to many devices previously available, crushing damage still was often induced to a large degree when the dead ends of the Butz et al. patent were not carefully installed particularly under field conditions. Also, prior pulling devices, such as comealongs, tended to induce crushing forces into the line where they gripped the line to pull it.

Longitudinal displacement of the strands of a rope or similar stranded structure is a condition wherein the strands are displaced longitudinally with respect to each other. There may also be some longitudinal displacement of the elements within given strands. This may be induced by the gripping action of certain gripping devices, and is often

2

encountered when care is not exercised in applying a helically performed dead end to a relatively flexible stranded structure. Although this displacement may take place to a minimum degree in metal ropes and strands, it is normally not of a significant nature. However, in fiber glass rope, this longitudinal displacement may be sufficient to permit substantial uneven or unequal longitudinal loading of the strands and elements comprising the line. When such unequal loading occurs, failure of the overloaded strands or elements may occur resulting in overloading the remaining strands or elements which successively fail until ultimate failure of the line occurs.

Also other gripping and pulling problems are encountered when using prior art gripping and pulling devices on certain roped structures. For example, fiber glass rope is normally provided with a jacket of plastic or elastomeric material for protection. With prior art gripping devices this jacket had to be stripped in the region to be gripped before applying the gripping device, since application of gripping devices over this jacket produces widely varying failure loads. This stripping operation was time-consuming and also the underlying rope structure could be damaged by this removal operation.

One of the most widely used prior art techniques of securing the end of a fiber glass rope was "potting" or encapsulating. In a potting technique, the end portions of the fiber glass rope are first stripped of the jacketing material, and then encapsulated within a fitting by a resin which is allowed to cure inside of the fitting with the rope surrounded thereby, thus securing the fitting to the rope.

The encapsulated, or potted fitting has been the conventional, or standard prior art fitting for many types of lines including fiber glass rope. In fact this is the type of fitting normally applied to test the strength of the fiber glass rope. These potted fittings while representing the standard, have many serious limitations.

First, the fittings require a great deal of skill to apply properly, especially under field conditions. The line and the fittings must be properly prepared and ingredients must be carefully measured. Also the process of applying potted fittings is time consuming, not only in the preparation of the fittings and the line and the mixing of the ingredients, but also because of the time required for the encapsulating material to set. These drawbacks have restricted to some extent the use of fiber glass rope.

Since fiber glass rope has many attractive features for guying purposes for many structures, such as antenna towers, it is especially desirable to overcome these problems to permit effective use thereof for these and other applications.

In accordance with the present invention, a line engaging device is provided which is comprised of an inner layer of helically performed elements, applied to the line, and a gripping member having helically preformed elements wrappingly engaging the inner layer with means for attachment of the gripping member to an anchoring structure. This configuration minimizes the crushing forces induced into the line and also minimizes any longitudinal displacement of the strands or elements of the strands. Also, this arrangement can be applied over the jacketing material of the fiber glass lines.

This dual layer configuration of the gripping device also provides a useful device to grip lines for the pulling thereof, for applying tension thereto.

Still other advantages of the invention together with a fuller understanding thereof will become apparent from the following description taken in conjunction with the accompanying drawings in which:

FIG. 1 is a side elevational view of a helically pre-formed element made from a wire;

FIG. 2 is a broken elevational view of several of the elements of FIG. 1, formed into a sub-set;

FIG. 3 is a broken elevational view of several sub-sets of the elements of FIG. 2, wrappingly engaging a line to form a layering set;

FIG. 4 is an elevational view of a straight bight gripping member;

FIG. 5 is an elevational view of the member of FIG. 4, being wrappingly engaged onto a line over the layering set of elements;

FIG. 6 is a completed assembly of the gripping member applied over the layering set of elements;

FIG. 7 is an elevational view of the device of this invention being used as a line engaging element for applying tension to a line; and

FIG. 8 is an elevational view of still another embodiment of a gripping member applied over a layering set of elements on a line.

Referring now to the drawings, and for the present to FIG. 1, an individual resilient helically preformed wire element 10, is shown. This element 10 may be formed in several ways. However, preferably this forming is done as described in U.S. Pat. No. 2,588,663, issued to E. H. Schane. The helically bent wire is then severed into helically preformed elements 10 of the desired lengths. The elements may be stress relieved and the ends may be chamfered to eliminate sharp edges.

The element 10, thus formed is an open helix of hard drawn wire, such that it may be applied to a line from its side without permanent deformation of the helix.

A plurality of the elements 10, as shown in FIG. 1, are assembled into sub-sets as shown in FIG. 2, and these sub-sets can then be applied directly to a line L as shown in FIG. 3. If desired the elements in the sub-sets can have grit applied thereto to enhance the holding power as is well known in the art. As illustrated herein, three sub-sets of four elements each are applied to the line L. It is to be understood, however, that the number of elements in a sub-set as well as the number of sub-sets can also vary widely, as will be described presently. In the illustrated embodiment, the line takes the form of a fiber glass rope or cable. This particular material was selected for illustration inasmuch as the gripping devices of this invention are particularly useful with fiber glass rope or cable; however, it is to be understood that the device can be used effectively with any type of very flexible line. (As it is used herein the term "line" can include for example, a single wire or filament, a strand made up of a plurality of single wires, a cable or rope made from a plurality of strands, or wire made of a plurality of longitudinally extending elements. It applies to conductors of electricity as well as lines employed for guying purposes.)

Fiber glass rope is often supplied with a jacket formed of a plastic or elastomeric material such as urethane. Such a jacket is shown on the rope of FIG. 3, and designated with the reference character J. When such a jacket is supplied it is considered as part of the rope. As can be seen in FIG. 3, the layering elements 10 are applied over this jacket J. Hence, when such a jacket is supplied on the rope there is no necessity to remove the jacket, as with prior art gripping devices. (The reason why this device works effectively over the jacket is not completely understood, and in fact constitutes an unexpected benefit; however, certain theories of this and other improved results will be discussed presently.)

It is preferable that the elements 10 be formed to the opposite hand of lay from the lay of the line; i.e., if the line is right hand of lay the elements 10 will be left hand of lay and vice versa. However, it is contemplated that in some instances the rods 10 may be of the same hand of lay as the line and give satisfactory performance. Also, preferably the number of elements in a sub-set and the number of sub-sets is selected such that when they are applied they will cover at least fifty percent of the sur-

face of the line, over which they extend, but have a total spacing between the elements, the extent of which would be sufficient for the introduction of at least one additional element of the same size. It is desirable that these elements 5 cover at least fifty percent of the surface to provide a firm holding base for the "gripping member" to be applied later, but that they do not cover the surface so completely that an additional element could not be applied. This provides a spacing which allows for easy installation of the elements 10, and also prevents bridging, 10 thus permitting each of the elements 10 to securely bear against the underlying line. Preferably the elements 10 of the sub-sets are relatively small cross section and are comprised of a relatively large number of wires. This is so 15 that the elements can be applied easily and will not exert excessive pressure on the line. Also, this will provide a certain amount of desirable flexibility to the rope although it will stiffen the line sufficiently for the ease of application of the gripping device thereover. Additionally, a large 20 number of small elements provide greater contact area with the underlying jacket, than a fewer number of larger size elements covering the same area.

The applied sub-sets of helically preformed elements 10, provide an underlying or layering set of elements over 25 which a gripping member or device can be applied. The gripping device can take one of many forms incorporating preformed helical elements for grippingly engaging the set of layering elements. One desirable and preferred form is shown in FIG. 4, and designated by the reference character 12. As shown the gripping device 12 is 30 comprised of a plurality of hard drawn wire elements 14, having helically preformed end portions 16, and an intermediate substantially straight portion 18, joining the helically preformed end portions. The preformed portions 35 16, of each of the elements 14, substantially conform to each other as to pitch, length and internal diameter. The elements 14 are positioned in side-by-side relationship with one another to form a group, and the group of elements is bent within the intermediate straight portion to 40 form a bight section 18', which is free of a complete revolution. The opposite end portions 16, of the elements 14, extend from the straight bight section 18' and form a pair of legs 16'. This type of device is a conventional gripping device which, along with its method of manufacture, is 45 described in said Pat. 3,295,311. The gripping device shown in FIG. 4 is then wrapped over the layering set of elements 10, as shown in FIG. 5, with the legs 16' being 50 intertwined with each other, until they have been completely applied as shown in FIG. 6. Preferably, as described in said Pat. 3,295,311, the legs of the gripping device when intertwined with each other form more than 55 a half lay, but less than full lay coverage of the layering set of elements 10. (It is to be understood that the gripping members are applied over a set of elements which themselves do not cover 100% of the surface of the line, there being a space as described above; hence, when the 60 definitions of half lay and full lay coverage of the legs 16' contained in said Pat. 3,295,311 include percent coverage of the legs, the percent must be based on 100% theoretical peripheral coverage of the line by the elements 10, i.e., as if there were sufficient elements 10 applied to the line to provide 100% coverage of the underlying line.)

As can be seen in FIGS. 5 and 6, the hand of lay of 65 the legs 16' of the gripping device 12 is opposite to that of the elements 10, and the same as that of the line L. This opposite hand of lay is preferable, but it is contemplated that in some instances the legs 16' may be of the same hand of lay as the underlying elements 10 and 70 still give satisfactory performance. Because of this opposite hand of lay of the layering elements and the legs of the gripping device, and also because of the rigidity which the layering elements 10 provide, the relatively large diameter of wires of the gripping device can be relatively easily applied without encountering the difficulty 75

that is encountered when trying to apply such large diameter of wires directly to a flexible body, such as the underlying fiber glass rope and particularly when trying to apply the legs with the same hand of lay.

Also, as can be seen in FIG. 6, the underlying or layering set of elements 10 preferably extends past the end of the legs 16' of the gripping device 12. This configuration assures that the entire length of the gripping device 12 will be in effective engagement with the underlying structure. This extra length also provides for a stepped transition of flexibility; i.e., the line itself beyond the underlying set of elements is extremely flexible, while the line between the end of the layering elements and the end of the legs 16', is made somewhat less flexible by the layering elements 10, and the line covered by both the layering set of elements and the gripping elements is quite stiff.

As can be seen in FIGS. 5 and 6, the bight 18' of the gripping device 12 is disposed to engage an anchoring structure A, and thus form a dead end.

Tests performed demonstrated that fiber glass ropes dead ended according to this invention as shown in FIG. 6, consistently developed greater load carrying capacities than were developed with lines dead ended according to conventional prior art encapsulating or potting techniques. To test the strength of the dead end, the fittings (either the dead end fitting according to this invention or the potted fitting according to prior teaching), are applied to opposite ends of the rope and gripped in a tensile testing device. Tension is applied until failure occurs. As can be seen from the table below, the fiber glass rope dead ended according to this invention consistently carried a higher load than fiber glass rope dead ended by conventional potting techniques.

TABLE.—TENSILE TEST ON $\frac{7}{16}$ INCH FIBER GLASS ROPE MANUFACTURED BY PACKARD ELECTRIC DIVISION OF GENERAL MOTORS SOLD UNDER THE TRADEMARK "GLASTRAN"

Test No.:	Fitting	Rope breaking strength, pounds
1	Potted fitting 1	18,700
2	do	18,400
3	do	18,150
4	Dual layer device 2	18,900
5	do	19,100
6	do	19,200
Average of tests, 1, 2 and 3		18,417
Average of tests, 4, 5 and 6		19,067

¹ Standard encapsulating technique employed—metal socket fitting for each end was degreased and acid treated, the jacket at each end of the strand was removed and the strands unwound; the unwound strands were degreased and then inserted into the fittings; epoxy resin and hardener poured into the socket and allowed to cure.

² A layering set of helically preformed rods of the type shown in FIG. 1, was applied to each end of the strand over the jacket; the wires were of opposite hand of lay from the strand. A gripping member as shown in FIG. 4, was applied over the layering elements at each end, the hand of lay of the legs was opposite to that of the layering elements and the same as the strand.

As can be seen from the table above, in each instance line gripping devices formed according to this invention produced superior results to the standard prior art encapsulated devices and techniques. Further, fittings according to the invention not only develop a higher load carrying capacity, they can be simply and rapidly applied under virtually all field conditions.

Not only does the gripping device formed according to this invention provide a superior device for securing lines to an anchoring structure, it also provides a superior device for gripping a line to apply tension thereto during the installation of the line.

FIG. 7 shows somewhat diagrammatically gripping devices according to this invention, used both to apply tension to a line and to secure the line to an anchoring structure. First, one end of the line is secured to an anchoring point (not shown) usually on the tower or pole. Then the point on the line at which it is to be gripped to apply tension is selected, at which point a first set

of layering elements 110, is applied over which a first gripping device 112, is applied. The application of the layering elements 110 and the gripping device 112, is accomplished as described above. A tension applying device in the form of a comealong 20, is provided which has a hook 22, at one end, disposed to engage an eye 24, formed in the anchoring structure to which the other end of the line is to be connected. The other end of the comealong is provided with a hook 26, attached to a ratcheting device 28, which in turn is connected to the hook 22 by a chain 30.

The ratcheting device 28, is operable by a handle 32, which will move the ratcheting device 28, along the chain 30.

In order to apply the desired tension to the line, the hook 22, is engaged with the eye 24, and the hook 26, is engaged with the bight 18' of the gripping device 112. The handle 32 is then operated to move the ratcheting device on the chain 30 which will tighten the line. When the desired tension has been applied to the line, the line is cut to the desired length. The end of the line is then dead ended. This dead ending preferably is done with layering and gripping elements according to this invention. A second set of layering elements 210 is applied, in a manner as described previously, over which a gripping device 212, is applied also in a manner as previously described, engaging the anchoring structure A. The tension can be relieved from the tensioning device 20, transferring the load to the gripping device 212. The first gripping device 112 and the layering elements 110 can then be removed. These elements of course may be reused for additional tensioning operations if they are not severely damaged.

One of the outstanding advantages of using the mechanism of this invention for a device to apply tension, is that it does not cause any crushing damage to the underlying strand, such as is often the case with conventional prior art gripping jaws of tensioning devices. Tests were performed to show the effect of using conventional prior art gripping jaws to apply tension to a line as compared to the device of this invention. These tests were performed successively on test specimens of $\frac{7}{16}$ inch Glastran fiber glass ropes. For each test one end of the specimen was first dead ended with similar layering elements and a straight bight gripping device according to this invention as shown in FIG. 6. Next the specimen was wrapped with a set of layering elements 110 near the opposite end thereof at the place where it was to be gripped for tension to be applied. The same size and type of elements were used for each specimen. On one specimen, a gripping device 112, according to this invention was applied over the elements 110, in the manner as shown in FIG. 7 and engaged with the tensioning device 20. On the other specimen a conventional gripping jaw comealong was applied over the set of elements 110 and engaged with a tensioning device 20. In each test the line was tensioned to about 5,000 pounds by the tensioning device.

In each test the other end of the specimen was dead ended with similar sets of layering elements and a gripping device, according to this invention. The tension was released and the gripping device, the tensioning device, and the layering elements underlying were removed.

The specimens were each tensile tested by applying force thereon through the gripping devices at opposite ends. The specimen which had been gripped by a gripping device according to this invention, did not break until it had exceeded its full rated breakage strength, in fact, breaking above 19,000 pounds with failure occurring at a location away from where it had been gripped by the gripping device for tensioning. On the other hand, the specimen that had been gripped with the conventional gripping jaw type device failed at about 5,000 pounds, failure occurring at the place the where the jaws had gripped the specimen. These tests demonstrated that even covering the line by a set of layering elements would not

prevent damage to the line by the jaws of conventional gripping devices to such an extent that it was materially weakened and hence failed well below its rated breaking strength.

The gripping devices of this invention and method of using them in applying tension to a line have been described in conjunction with using similar gripping devices for a dead end; however, it is to be understood that the gripping devices and their use in applying tension are not limited to situations where similar type of devices are used to dead end lines, and they can be used in conjunction with other dead ends or dead ending devices and techniques.

Referring now to FIG. 8, another form of a gripping device applied over the underlying sets of wires 10 is shown. In this embodiment the gripping device includes a plurality of helically preformed wires 34, which are secured together at one end portion thereof, by a socketing device 36. The helically preformed wires 34 are formed to a common pitch length and internal diameter to engage over the layering set of wires 10. The socket device includes attachment means, in the form of a clevis pin 38, which is adapted to engage an anchoring structure. The helically preformed wires 34, can be secured in the socketing device by any of several conventional means. For example, the wires may be held in the socket by a swaging or wedging action as shown in application Ser. No. 729,610, filed May 16, 1968, now Pat. No. 3,575,519 entitled "Gripping Device," or they may be held in the device by encapsulating material as disclosed in application Ser. No. 729,618, filed May 16, 1968, entitled "Dead Ending Device," or application Ser. No. 729,619, filed May 16, 1968, now Pat. No. 3,551,959, entitled "Detachable Socketed Dead End." These of course are just illustrations of types of socketing devices and not intended as limiting.

The illustration of both the socket type gripping devices, and the type where preformed wires are bent to form a bight, are intended to be merely illustrative of the many configurations of gripping devices utilizing preformed helical elements which may be used. These forms are especially desirable for fiber glass rope application since they minimize torsional stress induced to the line and fiber glass is especially torque sensitive. However, it will be readily apparent to those skilled in the art that there are many other configurations which will function as gripping devices for engaging over the layering elements 10, the illustrated embodiments merely representing preferred structures which perform quite satisfactorily.

The exact reason for the excellent performance of the devices of this invention over other devices, particularly over helically formed devices applied directly to a line, is not completely understood. However, it is believed that there are several contributing factors which when taken together produce the outstanding performance. First, rope made of a plurality of strands which in turn are made up of a plurality of elements is an extremely flexible structure. When it is attempted to place relatively stiff helically preformed wires on this flexible structure, difficulty is encountered in that the rope tends to flex excessively when the wires are being applied, which makes the installation difficult. If under these circumstances, the grip is not carefully applied the operation tends to produce longitudinal displacement of the strands and elements with respect to each other, which as described above, can contribute to premature failure of the structure, particularly in the case of fiber glass rope.

Also, when helically preformed wires which are to carry the pull are directly applied to rope structure, it is necessary that the wires have the same hand of lay as the rope structure. If they are opposite hand of lay and tension is applied, the result is that the gripping device tends to unravel the rope under tension which contributes to rope failure. Hence, it is necessary when applying gripping devices directly to stranded structures that

the helically preformed wires have the same hand of lay as the rope. This increases the difficulty of application and increases the chance of longitudinal displacement of the strands or elements if care is not exercised in applying the device.

Further, when wires of the same hand of lay are used there is minimum number of pressure points where the wires are bearing against the rope, which tends to increase the concentration of the forces rather than disperse them, contributing to or increasing the possibility of crushing damage.

The dual layers structure of the present invention overcomes these disadvantages.

First, the underlying set of wires can be formed of thinner, less rigid members which can be more easily applied to the flexible rope structure. This is possible since the gripping action is not generated by these wires, and hence, the great strength required to provide the gripping action is not required.

Also, the underlying wires 10, can be of the opposite hand of lay of the rope, which makes application to the rope much easier. This provides a much improved structure for distribution of forces since wires having the opposite lay have a greater number of contact points with a great number of strands, thus, increasing the force distribution. The heavier wires of the gripping device can then be applied over the underlying set of wires 10. This underlying set of wires 10, will greatly reduce the external flexibility of the wires to the desired amount, increasing the ease of application of the gripping device, thereto.

Also, the wires of the overlying gripping device 12, will be the opposite hand of lay of the underlying wires 10, and the same hand of lay as the line L. This then allows the gripping device to be more easily applied to the underlying set of wires 10 and still retain the same hand of lay as the underlying rope structure, so that detrimental unwinding does not occur under tension.

This structure of opposite hand of lay of underlying wires and rope on one hand and underlying wires and overlying gripping device on the other provides an extremely desirable configuration for preventing concentration of gripping forces in any one area widely distributing these forces so that they do not contribute or cause a crushing action of the underlying structure. It also provides a configuration which is relatively easily applied to the structure which will not tend to cause longitudinal displacement of the strands and elements making up the underlying structure, and which will afford an extremely effective device for transferring load from the underlying rope structure up to the full potential of the rope itself.

While several embodiments of this invention have been shown and described various adaptations and modifications can be made without departing from the scope of the invention.

What is claimed is:

1. A device for gripping an elongated body comprising, a first set of helically preformed resilient elements formed to a common pitch length and internal diameter, said elements of the first set being of a size and adapted to be applied to wrappingly engage a body without permanent deformation of the elements; a second set of resilient elements, the elements of said second set having at least one end portion helically formed to a common pitch length and internal diameter and disposed for wrappingly engaging said first set of elements in overlying relationship when said first set is applied to the elongated body, means connected to said helically formed portions of said second set of elements for engagement with an anchoring structure.

2. The invention as defined in claim 1, wherein the first set of elements is configured and arranged such that when they are applied to a line there will be unfilled

space between the elements sufficient to accommodate at least one additional element of the same size.

3. The invention as defined in claim 2, wherein the configuration of the first set of elements provides at least 50 percent coverage of the underlying line of the portion of the line that will be covered thereby.

4. The invention as defined in claim 1, wherein the helically formed end portions of said second set of elements provide, upon intertwisting on the first set of elements, a less than whole lay gripping portion but more than half lay.

5. The invention as defined in claim 1 wherein the elements of said first set and the helically formed portions of said second set of elements are of opposite hand of lay.

6. The invention as defined in claim 1, wherein said first set of elements is longer than the helically formed portions of said second set of elements.

7. The invention as defined in claim 1, wherein the elements of said first set are substantially less rigid than the elements of said second set.

8. The invention as defined in claim 7, wherein the elements of said first set are of smaller diameter than the elements of said second set.

9. The invention as defined in claim 1, wherein said second set of elements are in side-by-side relationship defining a pair of helically formed leg portions connected by a bight portion.

10. The invention as defined in claim 9, wherein said bight portion is free of a complete helical revolution.

11. The invention as defined in claim 1, wherein the elements of said second set are secured by a socket member.

12. The combination comprising, a line, a gripping device therefore including a set of resilient layering elements and a set of resilient gripping elements, each of said layering elements being of similar size and helically preformed to a common pitch and internal diameter and wrappingly engaging said line, the elements of said gripping set having at least one end portion helically formed to a common pitch and internal diameter, said helically formed end portions of said gripping elements wrappingly engaging said layering elements in gripping relationship therewith, and means connected to said helically formed end portions of said gripping elements engaging an anchoring structure.

13. The invention as defined in claim 12, wherein the elements of said layering set are arranged such that there will be unfilled space between the elements sufficient to accommodate at least one additional element of the same size.

14. The invention as defined in claim 13, wherein the layering set of elements provided at least 50 percent coverage of the underlying line of the portion of the line covered thereby.

15. The invention as defined in claim 12, wherein the helically preformed end portions of said set of gripping elements provide, upon intertwisting on the first set of elements, a less than whole lay gripping portion, but more than half lay.

16. The invention as defined in claim 12, wherein the elements of said set of layering elements and the helically preformed end portions of the gripping elements are of opposite hand of lay.

17. The invention as defined in claim 16, wherein the line is a stranded structure and of opposite hand of lay as the set of layering elements.

18. The invention as defined in claim 12, wherein said set of layering elements is longer than the intertwined end portions of said set of gripping elements.

19. The invention as defined in claim 12, wherein the elements of said layering set are substantially less rigid than the elements of said gripping set.

20. The invention as defined in claim 19, wherein the elements of said layering set are of smaller diameter than the elements of said gripping set.

21. The invention as defined in claim 12, wherein the elements of said gripping set are in side-by-side relationship providing a pair of helically formed leg portions connected by a bight portion.

22. The invention as defined in claim 21, wherein said bight portion is free of a complete helical revolution.

23. The invention as defined in claim 12, wherein elements of said gripping set are secured by a socket member.

24. A method of tensioning a line to a predetermined amount comprising the steps of: providing a set of layering elements, said layering elements being helically formed to a common pitch length and internal diameter and configured for wrappingly engaging the line to be tensioned, providing a gripping member including a plurality of elements having end portions helically formed to a common pitch length and internal diameter and configured for wrappingly engaging said layering elements, and engagement means connected to said helically formed end portions of said elements of the gripping member for engagement with a structure, wrappingly engaging said set of layering elements on said line at a selected location; wrappingly engaging the helically formed end portions of the elements of said gripping device around said layering elements, engaging an anchoring structure and the engagement means of said gripping device with a tension applying device, and applying the desired tension to said line.

25. The method as defined in claim 24, wherein said line is connected to an anchoring structure after the desired tension has been applied.

26. The method as defined in claim 25, wherein said line is connected to said anchoring structure by the steps of providing a second set of layering elements, wrappingly engaging said second set with said line, providing a second gripping member, wrappingly engaging said second gripping member with said layering elements and engaging said engagement means with said anchoring structure.

27. A device for gripping an elongated body comprising, a set of helically preformed resilient elements formed to a common pitch length and internal diameter, said elements of the set being of a size and adapted to be applied to wrappingly engage a body without permanent deformation of the elements; and gripping means disposed to grippingly engage said set of helically preformed elements when said set is applied to the body, said gripping means including means to engage an anchoring structure to secure the line thereto.

28. The combination comprising, a line, a gripping device therefore including a set of resilient layering elements, each of said layering elements being of similar size and helically preformed to a common pitch and internal diameter and wrappingly engaging said line, and gripping means grippingly engaging said layering elements, said gripping means including means engaging an anchoring structure and securing the line thereto.
